UNITED STATES PATENT OFFICE.

GEORGE MCKERAHAN, OF ALTOONA, PENNSYLVANIA.

JET-OPERATED AIR COMPRESSOR.

Application filed April 6, 1926. Serial No. 100,090.

The invention is an improvement in the jet operated air compressor for which Letters Patent No. 1,469,364 were issued to this applicant on October 2d 1923, and which 5 comprises a revolving air wheel having air chambers placed concentrically and lengthwise of the wheel's axis; and jet nozzles disposed at one end of the air wheel so as to discharge fluid pistons into the open ends 10 of the revolving air chambers as the latter pass successively across the jet. The air chambers are preferably given a helical direction around the wheel and the latter is given rotation either by the impact of the 15 jet on the helical chamber-walls or by external means connected to an extension of the air wheel's shaft.

The present improvement consists in the 20 use of an air chamber of which the helix angle, formed with the wheel's axis, gradually increases from the jet end to the discharge end of the air wheel, and the object of the invention is to make the helix angle conform to the gradual reduction of velocity of the 25 fluid pistons as these pass through the air chambers.

The drawings illustrate the application 30 of the improvement to a design in which the air wheel closely fits and rotates within a stationary casing, but it is equally applicable 35 to the construction shown in Fig. 5 of the aforementioned Letters Patent where the casing tightly fits and revolves with the wheel.

In the accompanying drawings Fig. 1 40 shows a central section through the jet nozzles, air wheel casing and discharge pipe; a full side view of the air wheel within its casing is exposed. Fig. 2 is a section on the line 2—2 of Fig. 1, being a transverse 45 section through the jet nozzles and the lower journal of the air wheel; this figure also shows an end view of the air wheel chambers and wheel casing. Figs. 3 and 4 are diagrams which more clearly show the nature of the improvement.

In the illustration Fig. 1 the helically 50 chambered air wheel 1 is disposed vertically and the chamber walls 2 form two sides of the air chambers 3, the chambers being closed on the circumferential side of the wheel by the stationary casing 4 in which the air wheel has a close running fit. The lower 55 end of the wheel has a journal 5 which rotates in bearing 6. A bearing collar 7 supports the weight of the air wheel and 8 is a

cup for lubricant. In the construction shown bearing 6 is made integral with the two jet nozzles 9. The nozzle structure supports the wheel casing 4 on lugs 10 by which the casing 60 is fastened to the nozzles. A common supply pipe 11 conducts the jet fluid to nozzles 9. Pipe 11 will connect with the discharge pipe of the jet pump, which is not shown, or with any other source which supplies the jet fluid 65 at the required velocity. The upper or discharge end of air wheel 1 has a journal 12 which rotates in bearing 13, this bearing being secured to the interior of discharge pipe 14 by means of the radial ribs 15. The outer end 16 of the discharge pipe will connect with a separator or vessel in which the 70 compressed air or other gas is separated from the jet fluid, the separator not being shown in the drawing.

The nature of the present invention will be more clearly understood by comparing the two diagrams, Figs. 3 and 4. On a reduced scale these diagrams represent the outer surface of air wheel 1 when the latter 80 is developed or unrolled to a plane surface. Only a single air chamber is shown on each diagram as these will suffice for illustration. Fig. 4 shows an air chamber 17 of which the helix angle is constant from the 85 jet end to the discharge end of the wheel, the direction of the chamber being a straight slope. Fig. 3 shows my improved air chamber. When the air wheel surface is unrolled flat the improved chamber 3 appears 90 as a curve which has a gradually increasing helix angle with the axis 18 of the air wheel.

The following explanation will make clear the important and useful effect of this improvement.

In this compressor the best efficiency will be obtained when the detached fluid pistons 95 pass straight through the air wheel without being affected by the revolving motion of the air chambers. The air compression is 100 virtually completed before discharge from the air wheel and consequently the velocity of the fluid pistons will be gradually reduced toward the discharge end of the wheel as a result of the accumulating resistance 105 of the air compression; and as the initial or entering velocity of the fluid pistons, because of their much greater velocity and energy at this stage will largely determine the rotating speed of the air wheel it follows 110 that the pistons, toward the discharge end, because of their reduced velocity, will par-

take somewhat of the revolving motion of the air chambers unless the helix angle is increased so as to make the helical lead of the chambers agree with the lower velocity of the fluid pistons.

Besides entailing a wasteful and injurious driving load upon the entering pistons a yet more serious effect of even a small arc of revolution by the pistons will be the generation, toward the discharge end of the wheel, of centrifugal action which will throw the pistons toward the circumference of the wheel and away from the bottom of the air chambers and creating at the latter place an open vent through which the compressed air will escape backward.

These large deductions from efficiency will be entirely avoided by gradually increasing the helix angle of the air chambers toward the discharge end of the air wheel as already explained. An incidental benefit will be a gradual drawing together of air chamber walls 2, owing to their reduced helical lead, and thus effecting a gradual reduction of the chambers' cross area without tapering the outside diameter of the air wheel or reducing the radial depth of the chambers; this reduction of cross area will insure a close fit of the fluid pistons as these advance toward the discharge end of the wheel.

The improvement will be especially useful in the case of liquid jets.

It may be stated that when the air wheel is rotated by a pulley or other means connected to an extension of the wheel shaft, the speed of the wheel in this case will be

made the same as if the wheel were driven freely by impact of a jet of equal velocity upon chamber walls of the same helix angle; ⁴⁰ helical air chambers preferably being always used in combination with liquid jets.

By referring to Fig. 2 it will be seen that the jet nozzles, in the direction of the air wheel's circumference, are given a width ⁴⁵ much greater than the width of one air chamber thus insuring that a body of piston fluid sufficient to completely fill the chamber's cross area will be discharged into each air chamber as it passes across the jet. ⁵⁰

The drawings show two jet nozzles but one nozzle or more than two may be used as required.

This compressor is suited for compression of other gases besides air and it may be ⁵⁵ used as a vacuum pump or exhauster if the necessary connections are made.

What I claim is:

In a jet operated air compressor, tubular air chambers disposed helically about a central shaft on which the wheel is rotated, and the helix angle, formed by said air chambers with the axis of the wheel, being gradually increased from the jet end to the discharge end of the air wheel; jet nozzles adapted ⁶⁰ and disposed to discharge a fluid piston which will completely fill the cross area of each air chamber as the open ends of the chambers successively revolve into alignment with the nozzles; and means at the ⁶⁵ opposite end of the air chamber wheel for receiving the discharge from the wheel chambers.

GEORGE MCKERAHAN.
